(57) CLAIM

The ornamental design for pants, as shown and described.

DESCRIPTION

FIG. 1 is a front view of pants according to a first embodiment of the design;

FIG. 2 is a rear view thereof;

FIG. 3 is a right side view thereof;

FIG. 4 is a left side view thereof;

FIG. 5 is a front perspective view thereof;

FIG. 6 is a rear view of pants according to a second embodiment of the design, the front, left side, and front perspective views being the same as FIGS. 1 and 4–5, respectively; and, FIG. 7 is a right side view thereof.

The symbol depicted in FIGS. 6–7 forming part of the claimed design is a registered trademark of Lululemon Athletica Canada Inc.
